ARTHUR HUDSON, OF CLIFTON, NEW JERSEY

ROTARY PUMP

Application filed July 26, 1930. Serial No. 470,893.

This invention relates to rotary machines, as fluid pumps or engines, in which the rotor has piston blades movable back and forth through its periphery and extending lengthwise of its axis and the cylinder has an abutment or partition to separate its inlet and outlet from each other and means to cam the blades inward in order to pass the abutment. Following the usual custom I depend, according to the present invention, on some force to hold the blades against the abutment and its camming means especially to attain good sealing contact against leakage from the inlet to the outlet direct, and instead of forming the structure including the abutment and cam means as usual with a pair (or opposite pairs in case the machine is reversible, as usual) of tapering cam horns, I form it as an apertured annular structure against which the blades under the centrifugal action bear continuously, this structure being preferably split and lap-jointed in some plane angularly related to the diameter occupied by the abutment whereby the section thereof having the abutment may be adjusted toward the other section to take up the wear produced by the blades and occurring, as it always does, principally at the abutment. Where cam means having horns or equivalent projections or the like characterized by terminals or ends are used there is always an attendant interference of the ends with the blades which disturbs the latter's action and also produces a hammering. Besides, my construction permits a lining as an element distinct from the abutment and cams to be omitted. I further provide for the positive outward movement of the blades, whereby the efficiency of the machine is greatly increased.

In the drawings,

Fig. 1 is a section on line 1—1, Fig. 2;

Fig. 2 is a vertical section of one form of the machine in the plane of its rotor axis;

Figs. 3 and 4 are side and front elevations of the mentioned annular structure;

Fig. 5 shows two blades and certain pins intervening between them;

Fig. 6 is a section on line 6—6, Fig. 7; 50

Fig. 7 is a vertical section of another form of the machine;

Figs. 8 and 9 are side and front elevations of its annular structure; and

Figs. 10 and 11 are inside and edgewise views of the cylinder heads for this form of the machine. 55

Figs. 1 to 5: The cylinder or casing is formed by the cylinder proper 1 and its two end walls or heads 2, all bolted together as shown in Fig. 2; the cylinder proper has the usual openings *a* and *b*, either of which may be the inlet and the other the outlet. 60

3 is the substantially cylindrical rotor fixed on shaft 4 journaled in the casing heads 2 and 5 its piston blades or members slidable radially in slots 6 in the rotor and, when the latter is rotated, held at their outward limit (as will appear) by centrifugal force. 65

The mentioned annular structure comprises 70 the abutment 7, two rings 8 connected thereby, and preferably a curved web 9 connecting the rings opposite the abutment; in fact, with the web present the structure is in effect a sleeve, with opposite apertures 10, each 75 bounded by the abutment, web and two rings. The rings (or this sleeve) are split at 11 into two sections one including the abutment and the other the web, when present, and preferably in a general plane which is perpendicular to that diameter of the structure cutting the abutment centrally. The splits 11 are actually lap-joints whose lapping surfaces 12 are in planes angularly related to the axis of the structure. The outer and inner surfaces of the structure are cylindrical, but the inner surface is offset eccentrically in a direction from the abutment or so that at the abutment its thickness is greatest. The annular structure fits the cylinder and is kept from rotat- 80 85

tive displacement by a rib 13 on the abutment fitting a groove 14 in the cylinder, the cylinder having adjusting screws 15 to bear against this rib. The ends of the section having the abutment are beyond the axis of the cylinder relatively to the abutment, wherefore, since the ends of said section bear against the cylinder, and if, of course, the inner surfaces of the two sections are initially flush, when adjustment of the section having the abutment toward the other section occurs this flush relation will be preserved as an incident of the ends of the former section being pressed together by the cylinder, as of course 10 would not result if the plane of division were between the abutment and said axis.

It will be understood that when the machine is operating the fluid moves from the inlet through one aperture 10, around the rotor 20 (and between it and web 9, if present) and then through the other aperture 10 to the outlet, direct communication from the inlet to the outlet being cut off by the abutment 7. The rings of course, due to the eccentricity 25 of their inner surfaces, which brings them flush with that of the abutment, cam the blades inward so as to pass the abutment, they thereupon returning (in short, always remaining in contact with the rings) as an incident of centrifugal force. The web 9 affords a surface against which in the working portion of the revolution of each blade the blade wipes in sealing contact, so that in that region there can be no escape of fluid past the 30 blades. In short the annular structure not only avoids the mentioned interference between its cams and the blades which characterizes the usual construction but it includes as a part thereof that surface (to wit, of web 35 9) which in a portion of the revolution of a blade coacts with the latter to seal off from each other the fluid bodies relatively ahead of and behind the blade; usually a lining is resorted to to afford such surface, but my 40 construction eliminates the lining as an element distinct from the abutment and cam device. If wear occurs which would allow leakage between the blades and the abutment this may be taken up by adjustment 45 of the screws 15, which sets the section of the annular structure having the abutment toward the other section.

To insure positive outward displacement of the blades I provide diametric holes 16 in the 55 rotor and in these place pins 17 which reach from each blade to the diametrically opposite blade; these abut the blades, leaving each free of the other to move outwardly under centrifugal force. If any blade tends to stick 60 in its slot the inward camming action on the other insures its outward movement.

Figs. 6 to 11: In this form the parts 1a to 15a are all substantially the same as the corresponding parts 1 to 15 in Figs 1 to 5 except 65 ing as follows: These views show that the

inner surface of the annular structure need not necessarily be truly circular, as in Figs. 1 to 5. They also show the means for positively moving the blades outwardly as comprising cam surfaces 18a which may be formed in endless grooves 18 in the inner faces of the heads 2a and studs 19 on the ends of the blades arranged to wipe against said surfaces. It will be understood that the outer sides of the grooves do not oppose centrifugal force 70 acting on the blades to hold them in sealing contact with the web 9a.

Having thus fully described my invention what I claim is:

1. A rotary machine of the class described comprising a cylinder having in its cylindrical wall a fluid intake and outlet, a rotor revoluble in the cylinder and having a piston movable toward and from and normally urged toward said wall of the cylinder, an annular structure extending around the rotor within the cylinder and outwardly abutted by the piston and apertured for passage of fluid from the intake to the outlet around the rotor and having an abutment opposing direct fluid flow from the inlet to the outlet and having its inner surface formed to cam the piston past the abutment, said structure being split in two sections in a plane angularly related to the diametric plane occupied by the abutment and said sections having their ends lapping and flush with each other at the inner periphery of said structure, and means to adjust the section having the abutment bodily toward the other section. 80

2. A rotary machine of the class described comprising a cylinder having in its cylindrical wall a fluid intake and outlet, a rotor revoluble in the cylinder and having a piston movable toward and from and normally urged toward said wall of the cylinder, an annular structure extending around the rotor within the cylinder and outwardly abutted by the piston and apertured for passage of 85

fluid from the intake to the outlet around the rotor and having an abutment opposing direct fluid flow from the inlet to the outlet and having its inner surface formed to cam the piston past the abutment, said structure being split in two sections in a plane angularly 90

related to the diametric plane occupied by the abutment and the section having the abutment having its ends lapping and flush with each other at the inner periphery of said structure, and means to adjust the section having the abutment bodily toward the other section. 95

3. A rotary machine of the class described comprising a cylinder having in its cylindrical wall a fluid intake and outlet, a rotor revoluble in the cylinder and having a piston movable toward and from and normally urged toward said wall of the cylinder, an annular structure extending around the rotor within the cylinder and outwardly abutted by the piston and apertured for passage of 100

fluid from the intake to the outlet around the rotor and having an abutment opposing direct fluid flow from the inlet to the outlet and having its inner surface formed to cam the piston past the abutment, said structure being split in two sections in a plane angularly 105

related to the diametric plane occupied by the abutment and the section having the abutment having its ends lapping and flush with each other at the inner periphery of said structure, and means to adjust the section having the abutment bodily toward the other section. 110

4. A rotary machine of the class described comprising a cylinder having in its cylindrical wall a fluid intake and outlet, a rotor revoluble in the cylinder and having a piston movable toward and from and normally urged toward said wall of the cylinder, an annular structure extending around the rotor within the cylinder and outwardly abutted by the piston and apertured for passage of 115

fluid from the intake to the outlet around the rotor and having an abutment opposing direct fluid flow from the inlet to the outlet and having its inner surface formed to cam the piston past the abutment, said structure being split in two sections in a plane angularly 120

related to the diametric plane occupied by the abutment and the section having the abutment having its ends lapping and flush with each other at the inner periphery of said structure, and means to adjust the section having the abutment bodily toward the other section. 125

5. A rotary machine of the class described comprising a cylinder having in its cylindrical wall a fluid intake and outlet, a rotor revoluble in the cylinder and having a piston movable toward and from and normally urged toward said wall of the cylinder, an annular structure extending around the rotor within the cylinder and outwardly abutted by the piston and apertured for passage 130

of fluid from the intake to the outlet around
the rotor and having an abutment opposing
direct fluid flow from the inlet to the outlet
and having its inner surface formed to cam
5 the piston past the abutment, said structure
being split in two sections in a plane angularly
related to the diametric plane occupied
by the abutment and having the ends of the
section having the abutment beyond the axis
10 of the cylinder relatively to the abutment
and bearing against said wall, and means to
adjust the section having the abutment bodily
toward the other section.

15 In testimony whereof I affix my signature.
ARTHUR HUDSON.
